UNITED STATES PATENT OFFICE.

EDWARD CRAIG, OF ST. JOSEPH, MICHIGAN, ASSIGNOR, BY MESNE ASSIGNMENTS, TO WIREBOUNDS PATENTS COMPANY, OF CHICAGO, ILLINOIS, A CORPORATION OF MAINE.

STAPLING-MACHINE.

1,211,823.

Specification of Letters Patent.

Patented Jan. 9, 1917.

Application filed September 20, 1909. Serial No. 518,582.

To all whom it may concern:

Be it known that I, EDWARD CRAIG, a citizen of the United States of America, and resident of St. Joseph, Berrien county, Michigan, have invented a certain new and useful Improvement in Stapling-Machines, of which the following is a specification.

My invention contemplates an improved machine for driving staples outwardly 10 through the walls of a box. For example, in the manufacture of wire bound boxes the end walls thereof are secured in place by staples or nails driven from the inside. With this method, the said staples or nails 15 first pass through the end walls of the box and then outwardly into the cleats.

Broadly considered, my invention contemplates a machine for stapling the heads or end walls to the cleats of a wire bound 20 box, having means outside of the box for making the staples upside down, and means inside of the box for driving the staples upwardly, whereby the staples need not be turned over after being made and before 25 being driven.

In the accompanying drawings, Figure 1 is a side elevation of a stapling machine embodying the principles of my invention. Fig. 2 is a horizontal section on line 2—2 30 in Fig. 1. Fig. 3 is a perspective of the staple former. Fig. 4 is a vertical section on line 4—4 in Fig. 1. Fig. 5 is an enlarged detail section on line 5—5 in Fig. 1. Fig. 6 is a perspective of one of the staples 35 made by my improved machine. Fig. 7 is a fragmentary perspective view of the receiving end of the trough or guide for the staples. Fig. 8 is a transverse section on line 8—8 in Fig. 15. Fig. 9 is a perspective 40 of one of the fingers that are employed to guide the staples into the trough. Fig. 10 is a perspective of the delivery end of the trough in which the staples are fed forward and finally delivered to the driver.

Fig. 11 is a vertical section on line 11—11 in Fig. 12. Fig. 12 is an enlarged detail section on line 12—12 in Fig. 2. Fig. 13 is a perspective of the block in which the staple-driver operates. Fig. 14 is a horizontal section on line 14—14 in Fig. 12. Fig. 15 is a detail plan view of that portion of the machine where the staples are made. Fig. 16 is a vertical section on line 16—16 in Fig. 15.

As thus illustrated, my invention com-

prises a standard A mounted on a base B and provided with a horizontal upper portion C. The portion C is hollow and contains the driving arm D which is pivoted at d. At its outer end the portion C, which 60 serves as a rest or table for the end of the box, is provided with the block E, which latter has beveled or converging outer sides e, as shown. This block E has a vertical recess e' in which the driver e² slides up and 65 down. This driver, it will be seen, has a block e³ that is engaged by the arm D, whereby the driver is moved up and down. The recess e' is open at its upper end, at e⁴, to permit the upward insertion of the staples 70 through the cleats and end walls of the box. At e⁵ the said recess is enlarged to receive the end of the trough or guide F, and the end of the guide bar G. It will be seen that the end of the said trough or guide F has 75 a spring lip f upon which the staple rests upside down immediately before it is delivered to the staple-driver e². The inner side surfaces of the box to be stapled bear against the sides e of the block E during 80 the operation of manipulating the box by hand on the rest C, and while the staples are being driven. Thus the block E serves as a guide for the box. The staples straddle the lower edge of the bar G, and rest upside 85 down in the trough F. One by one these staples are fed to the space above the driver e², and then driven upwardly.

An adjustable clamp H, mounted on the end of the arm h, holds the end of the box 90 down while the staples are being driven. The arm h is pivoted at h' upon the frame h², which latter is rigid with the portion C, and with the standard.

For certain broader purposes of my invention, the staples can be made in any suitable manner, but are preferably made on the machine. The rear end of the trough or guide F has a support f' over and upon which the wire is fed from the tube f². 100 Fingers f³, for engaging the sides of the staples, are secured upon the top of the rear portion of the trough or guide F. The rear end of the bar G, which is supported horizontally with its lower edge in the said trough or guide, is between the fingers f³ and just above the support f'. The staple former I is inverted and arranged to slide up and down in the frame of the machine. It has a slot i that receives the support f' 110

2
and the bar G, when the staple is formed. The upper ends i^1 and i^2 of the staple former are adapted to engage the wire and cut off a suitable length thereof and then bend the 5 same on the lower edge of the bar G. See Fig. 5. The lower end of the staple former has a pair of ears i^3 whereby it is operated by a link i^3 . The upper end of this link is pivoted on the end of the arm h. Thus each 10 time a staple is driven at the outer end of the trough F, another staple is formed at the other end of said trough or guide.

The reciprocating staple feeder J slides horizontally upon the end portion of the bar 15 G and has lateral recesses j which receive the fingers f^3 . This staple-feeder moves forward when the driver e^2 and former I are retracted to their normal or lower positions. In this way the one staple is driven while 20 the other is being made, and then all the staples are fed forward a distance equal to the thickness of the wire from which they are made. This brings a fresh staple into position to be driven the next time the driver 25 e^2 moves upward. Said staple feeder J has its rear end provided with a roll j' that is operated by a suitable cam j^2 on the driving shaft K. In this way the said staple feeder is reciprocated horizontally and in a direction lengthwise of the bar G. The feeder J is retracted to normal position by the 30 spring j^3 .

The arm D has a roll d' that engages the cam d^2 on the said operating shaft. The 35 arm h has a similar roll h^3 that engages a cam h^4 on said shaft. These cams are set oppositely, so that the arm D moves up when the arm h moves down. A spring h^5 connects the rear ends of said arms and holds 40 the said rolls in engagement with the said cams.

A spring L serves to retract the staple former to its normal or lower position, after 45 each staple is formed. The wire X for the staples is fed by rolls M into a tube m, and from the latter to the tube f^2 , and to the staple former. The lower roll has a ratchet mechanism m' operated by an arm m^2 . This arm is pivoted at m^3 and has its upper end 50 provided with a roll m^4 which engages a cam m^5 on the shaft K. A spring m^6 serves to keep the roll m^4 in engagement with the cam m^5 . Thus the wire is automatically fed and cut and formed into staples by mechanism 55 on the machine.

The bar G is preferably slightly thinner at the bottom than at the top. This gives the staples a slight flare or spread. Thus the outward spring or tension of the staples keeps 60 them tight against the fingers f^3 and in upright position when the feeder J is retracted.

From the foregoing it will be seen that I provide a very simple and highly efficient 65 stapling machine for doing work of the general character disclosed. It will be seen that

the staples are made and fed and driven in an inverted position. By this, I mean that the staples are made with their points upward, are fed forward in that position, and are driven in the same position. It follows, 70 therefore, that the staple former, the staple guide, and the staple driver are also inverted.

For the broader purposes of my invention; I do not limit myself to the use of 75 staples. Obviously, the mechanism may be changed or modified without departing from the spirit of my invention, so as to use nails or other fastening devices instead of staples. I am the first to make the staples upside 80 down, by mechanism outside of the box, feed the same forward into the box, maintaining the said staples with their points upward, and then drive them upwardly.

What I claim as my invention is:

1. In a box stapling machine, mechanism for making the staples with their points up, mechanism for feeding a row or series of the staples horizontally in the same position, mechanism for driving the staples upward, disposed a distance from the staple making mechanism, said row of staples with their points upward extending from the point where they are made to the point where they are driven upward, and means 95 serving as a gage by which the sides of the box may be successively engaged on the inner surface thereof to properly position the same relatively to the staple driving mechanism.

2. In a box stapling machine, a driving mechanism, a guide for directing a row or series of staples to said mechanism, a forming device arranged for making the staples at the distant end of said row, means 105 adapted to project inside of the box to gage the position thereof, and means adjacent said device for exerting pressure only on the end of said row, to feed all of the staples forward on the guide, keeping said 110 staples pointing in the same direction from the time they are made until they are driven.

3. In a box stapling machine, staple-driving mechanism, staple-guiding means leading thereto, staple-feeding mechanism for 115 moving the staples on the guiding means, a staple-forming mechanism arranged permanently a distance from the driving mechanism and between the guiding means and feeding mechanism, and means serving 120 as a gage by which the sides of the box may be successively engaged on the inner surface thereof to properly position the same relatively to the staple driving mechanism.

4. In a box stapling machine, a stationary 125 guide bar, means for forming staples on the under side of said bar, means for feeding the staples along the lower edge of said bar, means below the bar for supporting and holding the staples thereon, means for driv- 130

ing the staples, disposed a distance from the staple forming means, and means serving as a gage by which the sides of the box may be successively engaged on the inner surface thereof to properly position the same relatively to the staple driving mechanism.

5. In a box stapling machine, a guide for a row or series of inverted staples, mechanism for making the staples with their points up, mechanism for feeding the last or freshly made inverted staple onto the guide, to thereby feed all of the previously made staples forward, keeping them crowded tightly together, and means for driving the staples, the staple making mechanism and the staple driving means being disposed a distance apart.

6. In a box stapling machine, a driving mechanism, means for feeding a tightly compressed row of staples to said mechanism with their points uppermost, keeping said staples pointing in the same direction from the time they are made until they are driven, guiding means provided on the delivery end thereof with a spring lip for delivering the staples to the said mechanism, and means serving as a gage by which the sides of the box may be successively engaged on the inner surface thereof to properly position the same relatively to the staple driving mechanism, said driving mechanism and feeding means being spaced a distance apart.

35 7. In a box stapling machine, a stationary staple-guide, a staple former arranged to form staples with their points uppermost at one end of said guide, a staple driver arranged to drive staples with their points uppermost at the other end of said guide, said guide being formed with the same edge downward throughout its length, whereby all the staples between the said former and driver are upside down, means for moving 40 the staples along said guide from the former to the driver, keeping said staples pointing in the same direction from the time they are made until they are driven, and means serving as a gage by which the sides of the box may be successively engaged on the inner surface thereof to properly position the same relatively to the staple driving mechanism.

8. In a machine for driving fastening devices, mechanism for making the fasteners upside down, means for feeding a row or series of the fasteners upside down, by pushing on one end of the row to communicate the feeding motion through the row to 55 the other end thereof, mechanism for driving the fasteners one by one in an upward direction, whereby the fasteners retain their original position throughout their course of travel, and means serving as a gage by 60 which the sides of the box may be success-

sively engaged on the inner surface thereof to properly position the same relatively to the staple driving mechanism, said making mechanism and said driving mechanism being disposed at opposite ends of said row.

9. In a machine for driving fastening devices, the combination of a guide for holding a row or series of fasteners with their points extending upward in the proper direction for driving, mechanism for automatically delivering the said fasteners with their points upward to one end of said guide, keeping said staples pointing in the same direction from the time they are made until they are driven, mechanism at the other end of said guide for driving the fasteners one by one in the said direction, said delivering mechanism holding the staples always with their points upward, whereby the fasteners retain their original inverted position throughout their entire course of travel through the machine, and means serving as a gage by which the sides of the box may be successively engaged on the inner surface thereof to properly position the same relatively to the staple driving mechanism, said delivering mechanism and said driving mechanism being engaged at opposite ends of said row.

10. In a machine for driving fastening devices, a guide for holding a row or series of the fasteners in an inverted position, keeping said staples pointing in the same direction from the time they are made until they are driven, mechanism for automatically delivering the fasteners in an inverted position to one end of said guide, mechanism for automatically receiving the fasteners in an inverted position from the other end of the guide and driving the same, said delivering mechanism and guide holding the staples always with their points upward, whereby the fasteners retain their original inverted position throughout their entire course of travel through the machine, and means serving as a gage by which the sides of the box may be successively engaged on the inner surface thereof to properly position the same relatively to the staple driving mechanism, said delivering mechanism and said receiving mechanism being disposed at opposite ends of said row.

11. In a box stapling machine, means for making the staples with their points up, means for feeding the staples in a row with their points up, means for driving the staples upward at the outer end of said row, and means for engaging the inner surfaces of the box to gage the position thereof, the staple making means and the staple driving means being arranged at opposite ends of said row.

12. In a stapling machine, the combination with mechanism for driving the staples in an upward direction, of means for form-

ing the staples with their points uppermost, staple guiding means adapted to guide the staples points uppermost from a point adjacent the forming means to a point adjacent the driving means, means to support the staples by engagement with the bottoms of their bases, and means for feeding the staples along said supporting and guiding means.

10 13. In a stapling machine, the combination with mechanism for driving the staples in an upward direction, of a former plate, means to position a wire beneath said former plate, a pair of coöperating wipers, 15 means to carry said wipers in an upward direction to wipe the legs of the staple in an upward direction, means to support the staples by engagement with the bottoms of their bases, and means to feed the staples 20 along said supporting means point upper-

most as formed and present them to the driving mechanism.

14. In a stapling machine, the combination with mechanism for driving the staples in an upward direction, of wire feeding 25 means; wire severing means; wipers; a former plate; means to carry said wipers in an upward direction to wipe the legs of the staple in an upward direction; means to support the staples by engagement with 30 the bottoms of their bases, and means to feed the staples point uppermost and present them to the driving mechanism point uppermost.

Signed by me at St. Joseph, Michigan, 35
this 13th day of September, 1909.

EDWARD CRAIG.
